UNITED STATES PATENT OFFICE.

EDWARD L. PETIT, OF MOLINE, ILLINOIS.

VULCANIZING TOOL.

Application filed February 3, 1923. Serial No. 616,810.

To all whom it may concern:

Be it known that I, EDWARD L. PETIT, a citizen of the United States, residing at Moline, in the county of Rock Island and State of Illinois, have invented certain new and useful Improvements in a Vulcanizing Tool, of which the following is a specification.

My invention relates to vulcanizing tools, and has for its purpose to provide a simple and efficient instrument by means of which the inner tube of an automobile tire can be repaired, after being damaged. It is more specially designed to be carried on the vehicle, to be used on the road in case of a blow-out, or other injury to a tire, but it is also well adapted for use in a private or public garage.

One of the purposes of the invention is to provide a means for holding in place upon the inner tube what is commonly known as a "patch" while the vulcanizing operation is being performed. This is usually accomplished by the application of heat, and the tool is specially designed for use with that class of patches. It is equally useful, however, in attaching or cementing patches which are put on while cold.

Another purpose of the invention is to provide means for quickly positioning the tool on a section of the tube which is in need of repair, with the patch in proper place thereon, and as quickly releasing the same, after the work is done. It is also supplied with means for adjustment of the parts, so that it can be accommodated to differing thicknesses of material which is designed to be held thereby.

The above mentioned, and other features and advantages of the invention will more fully appear from the following specification, taken in connection with the accompanying drawings, in which:

Fig. 1 is a perspective of the invention, as the same appears when in use.

Fig. 2 is a plan view thereof.

The invention comprises a circular plate 1, provided with a handle 2, and a frame 3, having an extension 4, which has a hinged connection with a projection 5 of the plate 1, by means of a threaded pin 6, pivoted in the part 5, as at *a*, and passing upwardly through an opening in the extension 4. The threaded end of the pin 6 is fitted with a wing-nut 7, by means of which the part 4 can be held in adjusted positions with rela-

tion to the part 5. The frame 3 corresponds in shape and size with the plate 1, and is provided with a handle 8, fitted with an opening 9, to receive a toothed arm 10, pivoted in the handle 2, as at *b*. The teeth of the ram 10 are adapted for engagement with the handle 8, at the end of the opening 9, to hold said handle in locked relation with the handle 2.

11 represents a section of inner tube, in position in the tool, and 12 a patch which is being held against the tube by the frame 3. This patch usually consists of a small pan, containing inflammable matter, and a piece 70 of rubber or other adhesive material, which is caused to adhere to the tube 11 upon the application of heat thereto.

When the tool is being engaged with the tube, or being detached therefrom, the frame 3 can be tipped forwardly, at a right angle with the plate 1. In case the space between the plate 1 and frame 3 is too great to tightly grasp the section of tube, the parts can be brought closer together by adjustment of the nut 7. After the tube is in place, with the patch in position thereon, the handles brought as near together as possible, and locked by the arm 10. After the parts are vulcanized, the arm 10 is released, and the tool removed. The operations of engaging the tool with the tire, and removing the same therefrom, are reduced to a minimum of time and labor.

The plate 1 is of a solid formation, to hold the tube snugly up against the patch, but the frame 3 is of an open formation, to permit for the combustion in the part 12.

What I claim, and desire to secure by Letters Patent, is:

1. A device of the class described, comprising a plate provided with a handle at one edge and a projection at its opposite edge; a frame similar in form to said plate, also fitted with a handle on one of its edges and a projection on its opposite edge; and a connecting member between said projections, having a hinged attachment with one of said projections, and provided with means for holding the other projection in 100 adjusted positions with relation to the first-named projection.

2. A device of the class described, comprising a circular plate provided at one of its edges with a suitable handle and at 110 the opposite edge with a coupling member; a frame of similar form to said plate,

also fitted with a handle on one of its edges, and a coupling member on its opposite edge; coupling devices for said members forming a hinged connection therefor, and permitting an adjustment of one of said members with relation to the other; and means for uniting said handles, with said plate and frame in a clamping position.

3. A device of the class described, comprising a plate fitted on one of its edges with a handle and on its opposite edge with a coupling member; a frame of similar form, also provided with a handle on one of its

edges, coinciding with said first-named handle, and on its opposite edge with a coupling member; coupling devices for said members, having a hinged connection with one thereof, and having an adjustable connection with the other one thereof; and connecting means for said handles, adapted to hold said plate and frame in a clamping position, and provided with means of adjustment, to adapt said plate and frame to material of varying thicknesses.

In testimony whereof I affix my signature.

EDWARD L. PETIT.
